UNITED STATES PATENT OFFICE.

KENNETH J. UNWIN, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS.

LUBRICATING DEVICE FOR PICKER SPINDLES.

Application filed February 7, 1928 Serial No. 252,615.

This invention relates to improvements in lubricating devices for picker spindles of looms and it is the general object of the invention to provide such a device which will be dependent for its operation upon some part of the picking apparatus of the loom and may have a lubricating element which can slide along the picker spindle to deposit a film of lubricant.

- 10 The shuttles of looms are carried by lays which swing back and forth in the loom frame and as the lay moves backwardly the picker stick will act to propel the shuttle when the lay is approximately half way between its 15 front and back positions. In certain classes of looms the motion of the picker stick is communicated to the shuttle by means of a so-called picker which slides along a rod or picker spindle to be guided by the latter. It 20 is found that in fast running looms considerable difficulty is found in properly lubricating the spindles and it is an important object of my present invention to deposit a film of oil or other suitable lubricant on the 25 top and bottom of the spindle as well as the side thereof.

It is a more particular object of my present invention to provide a lubricant carrier which shall be pivotally mounted on a picker 30 stick actuated arm and having a portion to engage the spindle which is offset from the axis around which the carrier moves.

With these and other objects in view which will appear as the description proceeds, my 35 invention resides in the combination and arrangement of parts hereinafter described and set forth in the claims.

In the accompanying drawings, wherein I have shown a convenient embodiment of my 40 invention,

Fig. 1 is a fragmentary top plan view of one end of a loom having my invention applied thereto and showing the lay in its rear-most position with the lubricating element in 45 contact with the spindle.

Fig. 2 is a rear elevation taken in the direction of arrow 2, Fig. 1.

Fig. 3 is a view similar to Fig. 1 with certain parts removed and showing the picker 50 stick in shuttle propelling position with the lubricating device at rest,

Fig. 4 is an enlarged vertical section on line 4-4 of Fig. 2, and

Fig. 5 is a detail horizontal section on line 5-5 of Fig. 4.

I have indicated a loom 10 and a lay L having a shuttle box B in which may be located the shuttle S. The shuttle box has a back wall 11 against which the shuttle is held by binder 12 and there are projecting rearwardly from the shuttle box inner and outer lugs 13 and 14, respectively, which afford support for a picker spindle 15. Adjacent the inner end of said spindle there is located a conical bushing 16 which is seated in lug 13, said conical bushing receiving the tapered inner end of the spindle 15. The outer end of the spindle shown at the left of Fig. 1 extends through a bore 17 located in the lug 14 and is held in position against endwise movement by a screw 18. A picker 19 has a shuttle engaging portion 20 and extends through the wall 11 as shown in Fig. 1. Said picker is also provided with a bore 21 which receives the spindle 15 and that portion of the picker which lies between the bore and the shuttle is provided with a slot 22 through which projects the upper end of the picker stick 23. The particular method of mounting the picker spindle 15 forms no part of my present 80 invention and may be substantially the same as that shown in patent to Lanciault No. 1,594,620.

A stand 24 is secured to the loomside by a bolt 25 and extends to the left as shown in Figs. 1, 2 and 3 to afford support for a vertically extending stud 26 which is adjustable in a slot 26^a in the stand and is held in position by a nut 27. An actuating lever 28 is pivoted on the stud and has at the left hand end thereof a head 29 which may be covered with a strip of shock absorbing material such as leather, indicated at 30. The head may be provided with an incline 31 adapted for engagement by the picker stick 23 should the head lie in the path of the picker stick as the latter returns to inactive position after a shuttle propelling movement. The stand 24 and parts supported thereby which have been described may be substantially the same as set forth in co-pending application filed by Turner, Ser. No. 252,616, filed Feb. 27, 1928.

My present improvements relate more particularly to the form of lubricating element which has contact with the picker spindle 15 and in carrying my invention into effect I ex-

- tend the lever 28 to the right of the stud to form an arm 40. A stop pin 41 on the stand 24 limits movement of the lever under action of a torsion spring 42 one end 43 of which lies behind the lever 28 while the other end 44 extends behind a part of the fixed stand 24. As shown in Figs. 1 and 3 the action of this spring is to hold the head 29 in forward position and with the arm 40 against the pin 41.
- 10 A stud 50 is supported by and extends upwardly from the right hand end of the arm 40 and has pivotally mounted thereon a carrier element 51 having a finger 52 which is held against a stop pin 53 supported by the arm 40 by means of a coil spring 54. One end of said spring lies behind the carrier element as at 55 while the other end lies behind the arm 40 as at 56, and said spring is coiled around the axis of the stud 50 to hold the element 51 yieldingly relatively to the arm 40 in the position shown in Fig. 3.
- 15 The particular form of the element 51 which I employ herein is set forth in Figs. 4 and 5, where it will be seen that said element is provided with an oil reservoir 57 in which is located a wick 58. A pin 59 extending between the vertical walls 60 of the reservoir holds the U-shaped portion of the wick as set forth in Fig. 4, said wick being bent as at 61
- 20 and being held in this position by the pin 62. The reservoir is provided with a supply of oil which is raised by the wick so that the U-shaped portion lying opposite the pin 59 will be kept constantly saturated with oil.
- 25 As shown in Figs. 1 and 3 that portion of the element 51 which is adapted for cooperation with the spindle 15 is offset from the stud 50 with respect to the length of the spindle. This construction is of importance in the op-
- 30 eration of the device in that it causes the wick 58 to slide along the spindle and thereby deposit a film of oil of greater length than the length of the wick which is in contact with the spindle at any one time.
- 35 In operation the lay L moves back and forth in the loom and the picker stick will be moved from the position shown in Fig. 2 to the right to propel the shuttle. In a single box loom as shown herein the picker stick will be moved every alternate beat of the lay, being in the position shown in Fig. 1 on alternate beats and being in the position shown in Fig. 3 on intermediate beats when the lay is in its extreme rearward position. I do not
- 40 wish to be limited to this particular form of loom as the successful operation of my invention is not dependent upon the number of boxes in the lay. As the lay moves rearwardly on the beat that the picker stick 23 is non-
- 45 active the picker stick will engage the head 29 to rock the lever 28 in a counter-clockwise direction as viewed in Fig. 1 around the stud 26. The effect of this movement is to project the element 51 forwardly until the wick en-
- 50 gages the spindle as shown in Fig. 4, and in

dotted lines in Fig. 1, after which continued forward movement of the stud 50 and arm 40 will result in a side slipping movement of the lubricating element from the dotted to the full line position shown in Fig. 1. This action takes place while the lay is in its extreme rearmost position in the particular embodiment set forth in the drawings and as the lay moves forwardly the lubricating element will have a second longitudinal movement along the spindle to return to its normal position with respect to the arm 40, after which continued advancing movement of the lay will carry the picker stick away from the head 29 and the parts will be restored to the position shown in Fig. 3 by torsion spring 42.

On the next beat of the loom the picker stick will be operative to propel the shuttle and when the lay arrives at its rearmost position the picker stick will be moved inwardly or to the right to assume the position shown in Fig. 3. Under these conditions the lubricating element will remain at rest with the reservoir and wick out of the path of movement of the picker. In this way the device is called into operation every alternate beat of the loom, but as previously stated I do not wish to be limited to this particular arrangement and operation.

From the foregoing it will be seen that I have provided a lubricating device for loom picker spindles wherein a movable reservoir is caused to have a side slipping movement along one side and the top and bottom of a portion of the spindle, said movement being in one direction as the lay approaches the device and being in the opposite direction to return to normal as the lay moves away from the device. Furthermore, because of the side slipping action of the reservoir, close adjustments in the setting of the parts is not necessary.

Having thus described my invention it will be apparent that changes and modifications may be made therein by those skilled in the art without departing from the spirit and scope of the invention and I do not wish to be limited to the details herein disclosed, but what I claim is:

1. In a lubricating device for a loom having a lay movable back and forth in the loom and having a picker stick and a picker spindle, a device movable about a fixed pivot to have engagement with the picker stick as the lay moves, and a lubricating element pivotally mounted on said device and having a spindle engaging portion offset from the axis thereof, whereby movement of the lay will cause a side slipping movement of the lubricating device along the portion of the spindle.
2. In a lubricating device for a loom having a lay movable back and forth in the loom and having a picker stick and a picker spindle, a member movable by the picker stick as the lay moves, and a lubricating element piv-

totally connected to the member and having an offset spindle engaging portion, contact between the member and the picker stick moving the lubricating element first against the 5 spindle and then along the same by a sliding movement.

3. In a lubricating device for a loom having a lay movable back and forth in the loom and having a picker stick and a picker spindle, a lubricating member for the spindle movable by the picker stick as the lay moves first in contact with the spindle and then 10 along the spindle by a sliding movement.

4. In a lubricating device for a loom having a lay movable back and forth in the loom and having a picker stick and a picker spindle, and lubricating means actuated by the 15

picker stick as the lay moves to move along the spindle in a direction substantially parallel to the length thereof.

5. In a lubricating device for a loom having a lay movable back and forth in the loom and having a picker stick and a picker spindle, two devices pivoted together, one of which is positioned for engagement with the picker stick and the other of which is positioned to engage and then slide along the picker spindle to deposit a film of lubricant thereon when the first member is engaged by the picker stick.
